UNITED STATES PATENT OFFICE

158,769

TRUNDLE TOY

Otto Landy, Chicago, Ill.

Application July 7, 1948, Serial No. 147,413

Term of patent 14 years

(Cl. D34—15)

To all whom it may concern:

Be it known that I, Otto Landy, a citizen of the United States, residing at Chicago, in the county of Cook and State of Illinois, have invented a new, original, and ornamental Design for a Trundle Toy, of which the following is a specification, reference being had to the accompanying drawing, forming part thereof.

Fig. 1 is an elevational view of a trundle toy, showing my new design, with a portion of the handle broken away for convenience of illustration; Fig. 2 is a side elevational view also with a portion of the handle broken away.

Fig. 3 is a bottom view.

The dominant features of my design reside in the portion shown in full lines.

I claim:

The ornamental design for a trundle toy, as shown and described.

OTTO LANDY.
